US00D989951S

(12) **United States Design Patent** (10) Patent No.: **US D989,951 S**
Renou et al. (45) Date of Patent: ** Jun. 20, 2023

(54) **LABORATORY HAND INSTRUMENT AND UTENSIL**

Primary Examiner — Omeed Agilee

(71) Applicant: **TEOXANE S.A.**, Geneva (CH)

(57) **CLAIM**

(72) Inventors: **Julien Renou**, Geneva (CH); **Aurélie Pélégri**, Geneva (CH)

The ornamental design for laboratory hand instruments and utensils, as shown and described.

(**) Term: **15 Years**

(21) Appl. No.: **35/513,985**

DESCRIPTION

(22) Filed: **Mar. 24, 2022**

The file of this patent contains at least one drawing/photograph executed in color. Copies of this patent with color drawing(s)/photograph(s) will be provided by the Office upon request and payment of the necessary fee.

(80) **Hague Agreement Data**

Int. Filing Date: **Mar. 24, 2022**

1. Laboratory hand instrument and utensil

Int. Reg. No.: **DM/219801**

2. Laboratory hand instrument and utensil

Int. Reg. Date: **Mar. 24, 2022**

3. Laboratory hand instrument and utensil

Int. Reg. Pub. Date: **Apr. 8, 2022**

4. Laboratory hand instrument and utensil

(51) **LOC (14) Cl. 24-02**

5. Laboratory hand instrument and utensil

(52) **U.S. Cl.**

6. Laboratory hand instrument and utensil

USPC **D24/114**

7. Laboratory hand instrument and utensil
